TUBE HEATING MACHINE

James W. Garrett, Philadelphia, Pa., assignor to
 Selas Corporation of America, Philadelphia, Pa.,
 a corporation of Pennsylvania

Application April 23, 1948, Serial No. 22,931

15 Claims. (Cl. 214—18)

1

The present invention relates to furnaces and more particularly to a furnace in which tubes, or rods of various materials may be heated for drying, annealing, softening, baking or other purposes. The invention is herein described as being a softening furnace for glass tubes as that is one of the many uses for which it is adapted. In any case the operation will be the same, the difference being in the heat that is supplied for any given material and the speed with which the tubes or rods are moved through the furnace.

In the manufacture of curved fluorescent tubes for lighting purposes it is customary first to coat the interior of the tube with a fluorescent material, then to bake this material and soften the tubes so that they may be bent to shape. The furnace of the present invention will be described as being used for softening the tubes and baking the lining prior to the time the tubes are bent to their final form.

In the present invention there is provided a furnace chamber which has heat applied from the roof to objects to be heated that are moved progressively through the chamber by a novel work forwarding mechanism. While the tubes are being moved through the furnace chamber they are also rotated around their axes so that they will be evenly heated on all sides and will not sag to change their shape.

It is an object of the invention to provide a heat treating machine in which tubes or rods may be rapidly heated to some desired temperature. It is a further object of the invention to provide a heat treating machine in which tubes or rods are evenly heated on all sides as they are moved through a heating zone.

It is an object of the invention to provide a work forwarding mechanism of novel design for moving cylindrical objects through a heating zone of a furnace while rotating the objects. The work forwarding mechanism is characterized by a construction in which the parts thereof will always remain within the heating zone. Because of this no heat is lost as a result of the movement of the tubes.

It is a further object of the invention to provide an apparatus for rapidly and evenly heating tubes or rods in which the heat loss is reduced to a minimum. With the apparatus of the present invention only those parts that are designed to withstand the high temperatures developed are subjected thereto and they are not removed from the heated zone. The remaining parts and the operating mechanism are located out of the heated zone.

2

It is a further object of the invention to provide mechanism by means of which the interior of the tubes being heated may be purged or treated with some desired atmosphere while the heating is taking place.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

In the drawings:

Figure 1 is a section taken approximately on line 1—1 of Figure 2 showing a sectional view of the furnaces and forwarding mechanism, and a side view of the drive means;

Figure 2 is a view taken on line 2—2 of Figure 1;

Figure 3 is a plan view of a portion of the work forwarding mechanism;

Figure 4 is a view taken from the left of Figure 3 showing a portion of the work forwarding mechanism;

Figure 5 is a series of views illustrating diagrammatically the manner in which the work is forwarded through the furnace;

Figure 6 is a side view of a different embodiment of the work forwarding mechanism; and

Figure 7 is a top view of a portion of the embodiment disclosed in Figure 6.

Referring to Figures 1 and 2 of the drawing it will be seen that the machine of the present invention includes a suspended roof 1 by means of which the heat is supplied to the work as it is being forwarded through a furnace chamber which extends between the roof 1 and a floor 2. Located in the chamber between the roof and the floor is a work forwarding mechanism 3 by means of which work to be heated is moved from a feeding zone on the left of the machine to the right of the machine, where the heated work is received by mechanism to operate further upon it. The roof and floor are mounted on a suitable frame 4.

The roof is composed of a number of structural steel members 5 which are suitably joined together. Extending between these members are plates 6 to form a metal backing for the roof. The sides of the roof are composed of hollow castings 7 which extend from one end to the other thereof and form water cooled portions to

protect the remaining part of the mechanism from the heat. Across the front of the roof there is also provided a hollow casting 8 which forms a water cooled front for the outlet end of the machine. The metal framework described above has a lining of heat insulating material 10 beneath which are fastened refractory members 9 and burners 11. The refractory blocks and the burners are mounted within the framework of the roof so that the burners are located in rows across the same and in staggered relation to each other. The roof as a whole is pivoted on a rod 13 to be moved in a counterclockwise direction from the normal position shown in Figure 1. For this purpose there is provided a ring 14 on the upper portion of casting 8 through which a hook may be put so that a crane can lift the roof away from the forwarding mechanism for inspection and adjustment of both the roof and the forwarding mechanism.

The ends of the rod 13 are mounted in bearings 15 that extend upwardly from the rear portion of the framework of the machine. The frame also includes a pair of hollow castings 16 extending the entire length thereof to form water cooled sides. These castings are divided into upper and lower chambers as shown in the drawing, between which the work supporting members for the work forwarding mechanism extend into the furnace chamber.

From an inspection of Figure 2 it will be seen that in its normal operating position the roof is located with respect to the framework of the machine by means of engagement between flanges 18 projecting from the castings 7 of the roof to engage cooperating surfaces which are formed on the upper portions of the side walls 16 of the frame.

The burners 11 that are used in the present machine may be of any suitable type, but they are preferably of the type disclosed in Hess Patent 2,215,079, granted September 17, 1940, and reference may be made to that patent for a detailed description of the burners and their operation. Heat from the burners, as well as the exhaust gases resulting from the combustion, are directed downwardly against the work as it is passing under the roof, and the work is thereby heated to a degree depending upon the time required for the work to move through the furnace chamber and the temperature at which the burners are fired. Fuel is supplied to the individual burners through pipes 22 that are connected to a manifold 23. Valves 24 are provided in the pipes 22 so that each burner may be adjusted individually to provide the proper amount of heat to form a definite heat pattern for the work that is being heated. It is noted that there is an opening 25 provided in the left or rear end of the roof in Figure 1 through which the products of combustion are withdrawn. Any suitable type of suction means may be used for this purpose, and as the products of combustion are moved toward the rear of the roof they serve to preheat the work as it is moved into position under the roof.

The floor 2 of the heating chamber includes a steel backing plate 26 that is suitably reinforced with cross members 27. Lying against the face of the plate 26 is some suitable heat insulating material 29 above which are placed refractory blocks 28 to form a refractory floor just below the work forwarding mechanism. This floor is also heated by the heat radiated from the roof, and tends to reflect heat upwardly against the lower portion of the work as it is being moved through the furnace

chamber. The front end of the floor is provided with a passage 31 through which a combustible fuel can be supplied to a series of burners 32 extending across the front of the floor. These burners are of the type which produce a flame and they serve the purpose of blanketing the front end of the furnace chamber to prevent an inflow of cool air and also to give a final heating to the work as it is being moved out of the furnace and 10 is beyond the last of the burners 11 in the roof. The passage 31 is supplied with the combustible mixture through suitable tube 33.

The floor of the furnace is mounted for pivotal movement in a clockwise direction from the position shown in Figure 1 around a shaft 34 that is also mounted in the framework of the machine. This floor is normally held in the position shown by means of a fluid operated piston rod 35 and cylinders 36 that are pivotally connected to the 20 furnace floor and the machine frame respectively. Referring to Figure 2 it will be seen that the plate 26 forming the bottom of the floor extends beyond each edge of the heating chamber so that when the floor is in its normal position, this frame 25 will engage a surface formed on the bottom of the side frames 16. If desired, suitable gaskets can be used to prevent an inflow of air so that the combustion chamber will not be subjected to the cooling effects of air which may leak past 30 these joints throughout the length of the machine. It is noted that the tube 33 must be flexible since the floor can be moved.

The work is moved into the furnace chamber from the left through an entrance slot 42 which 35 has a water cooled upper wall 43. As the work, which in this case consists of glass tubes, moves through this slot it is fed piece by piece by feeding mechanism 44 to the sets of feed rollers 45 and 46. Alternate rollers are moved together 40 so that the mounting means of all of the rollers 45 are similar, while the mounting means of all of the rollers 46 are similar. These rollers are moved to both rotate the work and forward it through the furnace chamber. Each of the 45 rollers 45 is mounted on a shaft 45a, whereas each of rollers 46 is mounted on a shaft 46a. The rollers of each group or set are raised and lowered together and each roller is rotated continuously. Rollers 45 and 46 and their shafts are made of a 50 heat resisting alloy that will withstand the temperatures encountered in the furnace chamber.

The mounting means for the shafts 45a of rollers 45 (Figure 3) includes a casting or bracket 47 in which the left end of the shaft is journaled. 55 This casting is mounted for oscillation around a shaft 48 that is fixed in an upwardly projecting portion 49 of the frame. The casting or bracket in which the right end of the shaft 45a is mounted is indicated at 51. This casting is mounted for oscillation around shaft 52 that in turn is journaled for rotation in a bearing 53 projecting upwardly from the frame of the machine, as shown best in Figures 2 and 3 of the drawing.

Roller 45 is rotated by a gear 54 that is attached 60 to the right end of shaft 45a. This gear is driven by an idler gear 55 which is mounted on a stud shaft that is journaled in the casting, and the idler is, in turn, rotated by a gear 56 which is attached to the inner end of shaft 52. The outer end of shaft 52 has mounted on it a worm gear 57 that is rotated by a worm 58 on a shaft 59, extending parallel to the side of the machine and journaled in suitable bearings.

Rollers 46 are mounted in a similar fashion to that described above in connection with rollers

45 except that the driving mechanism for these rollers is on the opposite side or left of the machine. The right end of shaft 46a is mounted in a casting or bracket 61, which is in turn mounted for oscillation on a shaft 62 that projects from a support 63 extending upwardly from the frame. The left end of shaft 46a is journaled in a casting 64 that is, in turn, mounted for oscillation around a shaft 65 which is journaled in a bearing 66 projecting upwardly from the frame of the machine. Roller 46 is rotated by means of a gear 67 attached to the outer end of shaft 46a. This gear meshes with idler 68 that is on a stud shaft journaled for rotation in casting 64, and the idler is in turn rotated by a gear 69 attached to the inner end of shaft 65. The outer end of shaft 65 has mounted upon it a worm gear 71 that is rotated by a worm 72 on a shaft 73 extending lengthwise of the machine.

Each of the rollers 45 and 46 is mounted in the same way for rotation around an axis on a pair of castings while the castings upon which each roller is mounted are in turn oscillatable around a center that is axially aligned with the next adjacent shaft. Thus, while roller 45, for example, is being rotated it can also be oscillated around an axis that is in line with the axis of the next adjacent roller 46.

The castings 47 and 64 are so formed that there will be no interference between them as they are oscillated about their respective shafts 48 and 65. The same is true about castings 51 and 61. It will be seen that each casting 47 has a generally U-shaped portion extending between its end journaled on shaft 48 and its end that receives shaft 45a. Casting 64 also has a generally U-shaped portion between that portion thereof received on shaft 65 and that portion which receives shaft 46a. The U-shaped portion of casting 47 extends downwardly while that of casting 64 extends upwardly as shown in Figures 2 and 4. Therefore, while the castings have parts crossing each other as shown in Figure 3, there will be no interference as they are oscillated around their respective centers.

Castings 51 and 61 are formed similarly to castings 47 and 64 respectively. Casting 61 has a downwardly extending U-shaped portion between its ends, while casting 51 has an upwardly extending U-shaped portion between its ends.

The rollers 45 are raised and lowered in arcs around shafts 48 and 52, and rollers 46 are raised and lowered in arcs around shaft 62 and 65 in order to feed the tubes through the furnace chamber. The mechanism for oscillating the rollers will now be described.

Each casting 47 is provided with a downwardly extending arm 47a and in a like manner castings 51, 61 and 64 are provided with downwardly extending arms 51a, 61a, and 64a, respectively. Since the rollers 45 are mounted for movement together the lower ends of the arms 47a are joined by means of a rod 74 extending parallel to the side of the machine while the lower ends of arms 51a are joined by a rod 75 extending parallel to the other side of the machine. In like manner arms 61a are joined by a rod 76 while arms 64a are joined by a rod 77. Rods 74 and 75 are moved in unison to oscillate rollers 45 simultaneously and rods 76 and 77 are moved in unison to oscillate rollers 46 simultaneously. Rods 74 and 75 are moved respectively by levers 78 and 79 while rods 76 and 77 are moved respectively by levers 81 and 82. Lever 78 is attached at its midpoint, as shown in Figure 2, to a sleeve 83 which serves

as its fulcrum, and this sleeve is journaled in bearings 84 and 85 which extend downwardly from the frame of the machine. Lever 79 is free on a shaft 86 that in turn is journaled in the sleeve 83, and levers 81 and 82 are journaled on the outer ends of shaft 86. Levers 78 and 79 and sleeve 83 are oscillated by cams 87 and 88 to move the rollers 45. To this end the lower ends of levers 78 and 79 are connected respectively by links 89 and 91 to the upper end of levers 92 and 93. These latter levers have pins 92a and 93a respectively which engage in cam slots formed in the faces of cams 87 and 88.

In a similar manner levers 81 and 82 are oscillated by cams 88 and 87. To this end the lower ends of these levers are attached by links 96 and 97 to the upper ends of levers 98 and 99, respectively. Levers 98 and 99 are provided with pins 98a and 99a that extend into cam slots formed on the opposite faces of cams 88 and 87 respectively. The lower ends of levers 93 and 98 are journaled on a shaft 103 which in turn is held in position by supports 104. The lower ends of levers 92 and 99 are mounted for oscillation on a shaft 101 that is held in supports 102. The cams 87 and 88 are rigidly attached to a shaft 105 that is journaled in bearings 106. This shaft is rotated to rotate the cams and oscillate the levers to raise and lower rollers 45 and 46 by means of a sprocket 107 that is driven by a chain 108 from some suitable source of power.

The cam grooves which move levers 92 and 93 are so shaped with respect to the cam grooves that move levers 98 and 99 that only one set of the forwarding rollers 45 are being moved at a time. Thus, when rollers 45 are being moved upwardly rollers 46 are still, and vice versa. The cam grooves are so shaped that the movement of the rollers is sufficient to shift a tube from one pair of rollers 45, 46 to an adjacent pair of rollers 46, 45 in a manner to be described below. The last roller at the right end of the furnace chamber (Figure 1) is rotated, but not moved. Thus this roller provides a definitely located discharge point from the machine.

The feeding mechanism 44 for controlling the supply of tubes passing through entrance slot 42 to the forwarding mechanism in the furnace chamber is operated by the oscillation of tube 83 in synchronism with the movement of the rollers 45 and 46. The feeding mechanism consists of a pair of fingers 111 and 112 which are alternately projected into the path of movement of the tubes, as they are passing in the feeding slot 42 toward the furnace chamber. Finger 111 is pivoted at its lower end to a boss 114 which projects rearwardly from the tube 83 while finger 112 is pivoted at its lower end to a boss 113 which projects forwardly from sleeve 83. As the sleeve is oscillated in the manner described above the fingers will be raised and lowered. They are guided in their movement by a rod 115 that is suitably fastened in the frame of the machine and passes through slots which are provided for this purpose. It is noted from an inspection of Figure 2 of the drawing that two sets of the feeding fingers are used, one on each side of the machine toward the ends of the feeding rollers 45 and 46. These two parts of the feeding mechanism are operated together and are both operated by the sleeve 83. This means that the tubes will be maintained parallel to the rollers 45 and 46 as they are permitted to move into the furnace chamber.

The mechanical construction of a preferred

embodiment of the machine has been described, but it is believed that a description of the manner in which the various parts operate will be helpful. It is assumed that the burners in the furnace roof are operating and that the furnace chamber has been brought up to temperature. Some drive means, such as an electric motor, is used to rotate shafts 59 and 73 to rotate rollers 45 and 46 at a suitable speed. Drive means, which may be the same or a different motor acts through chain 108 to rotate the cam shaft 105, and a supply of tubes T to be heated has been placed in the entrance slot 42 of the furnace chamber. The sequence of operation will be described in connection with the diagrams of Figure 5 in which the sequences are lettered from A to H inclusive. It is noted that the parts of the mechanism in Figures 1 to 4 are shown in the positions they assume in diagrams C and G of Figure 5.

As cams 87 and 88 rotate they will act through the levers and links mentioned above to move rods 74 and 75 forwardly and rearwardly in unison, and will alternately act to move rods 76 and 77 rearwardly and forwardly in unison. As rods 74 and 75 move forward rollers 45 will be moved to their low position shown in diagram A of Figure 5. Then rods 76 and 77 will be moved rearwardly to move rollers 46 to their high position of diagram A of Figure 5. Finger 111 will be in its low position and finger 112 will be in its high position, so that a tube may roll against the first roller 46 as shown at II in diagram A. It is noted that when this occurs roller 46 is in its up position so that the tube will only move a short distance and cannot get broken. Continued rotation of the cams will bring the rollers to the same level as shown in diagram B and then to the relative positions of diagram C with rollers 45 higher than rollers 46. As this occurs tube I moves to the right to be supported by the second pair of rollers while tube II is supported by the first pair of rollers as shown in diagrams C and D. At the same time finger 111 has moved upwardly and finger 112 has moved downwardly to place the next tube in position to enter the furnace chamber.

Continued rotation of cams 87 and 88 will move the respective groups of rollers 45 and 46 to the positions shown in diagram E, and will at the same time lower finger 111 and raise finger 112. This permits a third tube III to move against the first roller 46. As the rollers move to the position shown in diagram F it will be seen that tubes II and III are supported on the first three rollers while there is a space between tubes II and I. As rollers 45 are raised, however, tubes I and II move to the right so that, as shown in diagrams G and H, each tube is supported on a separate pair of rollers. This spacing is maintained between the tubes during the entire time they are moving through the furnace.

As noted above, rollers 45 and 46 are continually rotated as they are being moved up and down. This results in the tubes being rotated continually about their own axes as they are being moved through the heating zone. Consequently the tubes are evenly heated all around and as the tubes get soft toward the end of their path of travel there is no tendency for them to flatten due to their own weight.

It is frequently desirable to force air or some inert gas into the tubes as they are being moved through the furnace chamber. This may be accomplished with the present machine by having

tubes through which the gas is forced extending along the lower portions of the water cooled sides 7 of the roof as shown at 116. These tubes are provided with one or more outlets 117 extending in the direction of the axis of the tubes and aligned therewith. By forcing a suitable gas through the tubes as they are being heated, treatment of a material inside the tubes may be accomplished.

In Figures 6 and 7 there is shown another type of mechanism for operating the rollers upon which the tubes are mounted as they are moved through the furnace chamber. In this embodiment of the device the sets of rollers are numbered 118 and 119. In the drawing only one end of each of the sets of rollers is shown since the type of operating mechanism for one end of rollers 118 is exactly the same as the type of operating mechanism on the other ends of rollers 119 and vice versa. Alternate rollers are driven from opposite ends. Therefore a description of the mounting and driving of one end of each of the rollers should be sufficient. Shaft 118a of roller 118 is mounted in an L-shaped supporting member 121 which has a downwardly extending arm 122. This member is pivoted on a shaft 123 that is in turn pivoted in a bearing 124. Roller 118 is driven by means of a sprocket 125 attached to the end of its shaft and a second sprocket 126 that is on the inner end of shaft 123. These sprockets are connected by a chain 127. Shaft 123 extends through the bearing 124 and has a second sprocket 128 on its outer end. This sprocket, along with the other sprockets 128 for the various rollers 118 is driven by a chain 129 which extends down the length of the machine, and is in turn driven in a suitable manner with a similar chain on the other side of the machine.

Shaft 119a for roller 119 is received in a bearing formed on one arm 131 of an L-shaped member whose other arm is indicated at 132. This member is pivoted to turn about a shaft 133 that is journaled in a bearing 134. The lower end of arms 122 are fastened together to be moved in unison as are the lower ends of arms 132 so that the various sets of rollers can be moved in unison. The means for moving arms 122 comprises a rod 135 that is pivotally attached to their lower ends and extends lengthwise of the machine. This rod has an enlarged head 136 on one end of it. In a like manner there is provided a rod 137 which is fastened to the lower end of the arms 132, that has on its end an enlargement shown at 138. These rods are moved back and forth in a horizontal direction in order to oscillate the roll holding members, and to therefore raise and lower these rollers, by means of a disc 139 that is mounted on a shaft 140. This disc has a drive roller projecting from each face with one roller 141 engaging the flat surface of the enlargement 136 and the other roller 142 engaging a similar flat surface of enlargement 138.

In the operation of the device disc 139 is rotated, and as it rotates the rollers 141 and 142 will alternately move the rods 136 and 137 in a horizontal direction. Since one roller is on one side of the disc and the other roller is on the other side of the disc the two rods will be moved in opposite directions. This movement is imparted through the supporting members for the rollers 118 and 119 to raise and lower the rollers alternately, and therefore to move tubes through the furnace in a manner similar to that de-

scribed in detail in connection with the embodiments of the invention of Figures 1 to 5 inclusive. It is noted that shaft 140 will prevent movement to the right of the enlarged portions of the rods 135 and 137 beyond the position of the shaft. This means that the rollers 118 and 119 in their positions shown in Figure 6 are at approximately the lowest position that they will assume. When drive rollers 141 and 142 move to the left of shaft 140, however, they will move the rods 135 and 137 through the full length of the stroke dependent upon the radial distance of the drive rollers from shaft 140.

It will be seen that in this embodiment of the invention as well as in the previously described one a means is provided for rotating the work forwarding rollers as their supports are being oscillated around a series of shafts. Thus, the work is progressively moved through the furnace chamber while it is being rotated.

In each embodiment of the invention there is provided a compact heating mechanism by means of which tubes or rods may be heated to a temperature depending upon the treatment to which they are being subjected. The heating of the work will be dependent upon the speed with which it is moved through the furnace as well as the temperature of the burners.

It is noted that only those parts of the mechanism that are designed to withstand the temperature of the furnace chamber are located therein. The remaining parts of the mechanism are outside of the chamber and protected therefrom by water cooled walls or the refractory work of the furnace chamber. Another advantage of the described construction is that those parts of the machine which are located in the furnace chamber remain in the chamber so that the heat they absorb will not be lost, as would be the case, for example, with a chain type or a car type work transporting mechanism.

While in accordance with the provisions of the statutes, I have illustrated and described the best form of embodiment of my invention now known to me, it will be apparent to those skilled in the art that changes may be made in the form of the apparatus disclosed without departing from the spirit and scope of the invention, as set forth in the appended claims, and that in some cases certain features of my invention may be used to advantage without a corresponding use of other features.

What is claimed is:

1. Apparatus for moving cylindrical objects through a heating structure including a furnace chamber having an entrance and an exit at opposite ends comprising in combination means to transport said objects through the structure including a plurality of elongated members extending in parallel relation across the chamber, each adjacent pair of members serving to support jointly an object, means to lift said members in sequence to move an object supported by an adjacent pair of members to the next adjacent pair of members in the direction toward the exit of the chamber, feed means to feed said objects one at a time to the entrance of the chamber, and means to synchronize the operation of said feed means and said lifting means so that an object is fed to the entrance of the chamber as the member adjacent the entrance thereof is in its lifted position.

2. Apparatus for supporting and moving cylindrical objects through an elongated work zone comprising a plurality of elongated members, a

bracket on each end of each member to support the same, means to mount each bracket for pivotal movement around an axis concentric with the member next to the member supported by a given bracket, means to connect the brackets supporting alternate members for movement together, and means to move in sequence said connecting means whereby alternate ones of said members will be raised to roll objects thereon from one member to the other through said work zone.

3. Apparatus according to claim 2 including means to rotate continuously said members.

4. Apparatus for moving cylindrical objects through a heating structure including a furnace chamber having an entrance and an exit at opposite ends comprising in combination supporting and transporting mechanism located at all times in the structure for moving objects from the entrance to the exit of the chamber including a plurality of elongated members, means to mount said members individually in parallel relation crosswise of the structure, each object being supported jointly by an adjacent pair of members, and means to move in sequence alternate ones of said mounting means to raise the members carried thereby above the level of the adjacent members to thereby move an object from one pair of members to an adjacent pair of members.

5. Apparatus for moving cylindrical objects through a heating structure including a furnace chamber having an entrance for said objects at one end, and an exit at the other end comprising in combination supporting and transporting mechanism located in the chamber to move the objects from the entrance to the exit thereof including a plurality of rollers, pivoted means to support individually said rollers, and means to move simultaneously alternate ones of said supports around their pivots to raise rollers carried thereby above the level of the remaining rollers whereby objects are rolled progressively along said rollers.

6. Apparatus according to claim 5 including means carried by said supporting means to rotate continuously said rollers.

7. Apparatus to move cylindrical objects through a treating structure including a chamber having an entrance at one end and an exit at the opposite end comprising in combination supporting and transporting mechanism for the objects located in the structure, said mechanism including a plurality of parallel rollers, individual supporting means for each roller, and means to move in sequence the supporting means for alternate ones of said rollers to raise first one group of rollers and then the other group of rollers above a given normal level thereof whereby objects on said rollers are progressively moved from the entrance end of the structure to the exit thereof.

8. Apparatus according to claim 7 including supply means for said objects to supply a single object at a time to the structure, and mechanism cooperating with said moving means to operate said supply means only when the roller adjacent thereto is in its raised position.

9. Apparatus to move cylindrical objects through a work zone including a chamber having an entrance at one end and an exit at the opposite end thereof comprising in combination a plurality of rollers, means to mount said rollers in the chamber for rotary movement around their axes and for lateral movement parallel to their axes, means to move alternate ones of said

11

rollers from a normal position to a position higher than said normal position to throw objects from between one pair of rollers to between the next pair, and means to rotate said rollers while they are being moved.

10. Apparatus for moving cylindrical objects through a work zone including a chamber having an entrance at one end and an exit at the other comprising in combination supporting and conveying means to move objects through the chamber including a plurality of elongated members, means to mount individually said members parallel to each other, means to support said mounting means for pivotal movement whereby said members will be raised above a normal position as said mounting means is pivoted, mechanism to pivot said mounting means including parts connected to alternate ones of said mounting means whereby as said mechanism is operated alternate ones of said members will be raised, and means to rotate said members continuously.

11. Apparatus for moving cylindrical objects through an elongated chamber having an entrance at one end and an exit at the opposite end, supporting and transferring mechanism to move objects through said chamber including a plurality of elongated cylindrical members, means to mount said members in parallel relation across said chamber, an object being supported jointly by two members, means operative to move simultaneously alternate ones of said members to a position above a normal position to shift objects supported thereby to the next pair of members, and means to rotate continuously each of said members.

12. Apparatus for supporting and moving cylindrical objects through an elongated work zone comprising a plurality of elongated members adapted to support an object jointly between adjacent members, means to mount said members in parallel relation to each other including a bracket on each end of each member, means to support each of said brackets for pivotal movement around an axis concentric with the member next to the member supported by a given bracket, and means to pivot in sequence adjacent pairs of brackets supporting a member to thereby raise successive members to a level above a normal level to thereby move objects from one pair of members to an adjacent pair of members.

13. Apparatus for supporting and moving cylindrical objects through an elongated work zone comprising a plurality of elongated members adjacent ones of which support jointly an

12

object, a bracket journalled on each end of each member, means to pivotally support each bracket for rotation around an axis coaxial with the member adjacent the one supported by a pair of brackets, means to move alternate pairs of brackets mounting a single member around their pivots to thereby move an object partially supported thereby to an adjacent pair of members.

14. Apparatus according to claim 13 including means to rotate each of said members in their respective brackets whereby said objects will be rotated as they are moved from one member to the other through said work zone.

15. Apparatus for moving cylindrical objects through a work zone comprising in combination, supporting and forwarding mechanism located continuously in said zone comprising a plurality of elongated members located in parallel relation and extending across said zone with the ends thereof extending outside of said zone, brackets to mount each end of said members for rotation about its axis, and means to move the pairs of brackets supporting each member from a normal position through a path concentric with the normal position of the next member in a direction toward the exit end of said zone, and means to operate said moving means to move adjacent members alternately through said path.

JAMES W. GARRETT.
